(57) **CLAIM**

The ornamental design for a controller for television surveillance system, as shown and described.

DESCRIPTION

FIG. 1 is a front elevational view of a controller for television surveillance system showing my new design;

FIG. 2 is a rear elevational view thereof;

FIG. 3 is a top plan view thereof;

FIG. 4 is a bottom plan view thereof;

FIG. 5 is a right side elevational view thereof; and

FIG. 6 is a cross-sectional view thereof.

The broken lines (immediately adjacent to the claimed areas in FIGS. 2-6) represent the bounds of the claim and the dotted lines in FIGS. 2-6 are for illustrative purposes only. None of the broken lines form part of the claimed design. The left side elevational view is a mirror image of the right side elevational view.
